UNITED STATES PATENT OFFICE

123,254

DESIGN FOR A TOOTHBRUSH

Clifford A. Williams, New York, N. Y., assignor to Berg-Williams Corporation, a corporation of Delaware

Application September 3, 1940, Serial No. 94,769

Term of patent 14 years

To all whom it may concern:

Be it known that I, Clifford A. Williams, a citizen of the United States, residing in the city, county, and State of New York, have invented a new, original, and ornamental Design for a Toothbrush, of which the following is a specification, reference being had to the accompanying drawing, forming a part thereof.

Fig. 1 is a rear view of a toothbrush showing my new design.

Fig. 2 is a front perspective view thereof.

I claim:

The ornamental design for a toothbrush, substantially as shown.

CLIFFORD A. WILLIAMS.
